ATTORNEY.

UNITED STATES PATENT OFFICE.

FRANK TUXWORTH, OF MANISTEE, MICHIGAN.

BRAKE FOR SAW-MILL LOG-CARRIAGES.

SPECIFICATION forming part of Reissued Letters Patent No. 9,916, dated November 1, 1881.

Original No. 237,457, dated February 8, 1881. Application for reissue filed June 24, 1881.

To all whom it may concern:

Be it known that I, FRANK TUXWORTH, of Manistee, Manistee county, Michigan, have invented a new and useful Brake for Saw-Mill Log-Carriages, (which has not been patented, to my knowledge or by my consent, in any foreign country,) of which the following is a specification, illustrated by the accompanying drawings.

10 My invention relates to what may be called "clamp-brakes;" and the object of my improvement is to apply the brake directly to saw-mill log-carriages.

Figure 1 of the drawings is a vertical end view of the brake. Fig. 2 is a side view of the brake applied to the rack-rail of the saw-mill log-carriage.

The same letters represent the same parts throughout the drawings.

20 A, Fig. 1, is the bed-plate of the brake, for attachment to the floor or other environment.

B B are pad-boxes, filled with pressed paper exposed edgewise, or other material suitable for braking purposes.

25 C C are the brake-pads, consisting of pressed paper projecting edgewise, or other material suitable for braking purposes.

D D are braces or abutments, rigid with the bed-plate A, one at each end of the pad boxes, 30 to keep the latter from rocking or swerving on the pressure being applied.

E E are lugs and pivots on the backs of the pad-boxes, for attaching the operating-levers.

F F are operating-levers, attached by pivot 35 and lug to the backs of the pad-boxes.

G G are adjustable fulcrums, with pivots for operating-levers, proper set-screws, and bolts for securing the fulcrums to the bed-plate.

H is a connecting-lever, attached by pivot 40 to standard-fulcrum I, and by connecting-rods to levers F F, for operating the latter. The long arm of the connecting-lever H should be of sufficient gravity of itself, or be so weighted, as to regain its perpendicular position and to 45 open the brake on the braking-power being relaxed.

I is a standard-fulcrum attached rigidly to the bed-plate A, and having pivot for connecting-lever H.

50 J J are set-screws for adjusting the fulcrums G G.

K K are bolts for securing fulcrums G G, when properly adjusted, to the bed-plate A.

L, Fig. 2, is the saw-mill carriage.

M is a rack rail or projection of the saw-mill carriage, attached firmly thereto and running longitudinally therewith, and passing between the brake-pads C C.

As will be readily seen by the drawings, when the connecting-lever H is operated by 60 a cord or chain—say extending from the end of its long arm over a pulley to a foot-lever or other power—it in turn will operate the levers F F, throwing out their long arms and bringing their short arms and the attached 65 brake-pads together upon the rack rail or projection M, Fig. 2, thus braking up the motion of the saw-mill carriage. When the pressure of the foot or other power is removed the gravity or added weight of the long arm of 70 the lever H will bring that lever to a perpendicular position again, bringing out their short arms, and thus relaxing the attached brake-pads and relieving the rack rail or projection of the carriage.

75

What I claim as new is—

1. In a brake for saw-mill log-carriages, the abutments or braces D, secured to a suitable base independent of the carriage, in combination with the pad-boxes B, adapted to move 80 between said abutments, substantially as described.

2. The abutments or braces D, secured to a suitable base independent of the log-carriage, as described, in combination with the pad-boxes and pads B C, moving between said abutments, mechanism, substantially as described, for moving said pad-boxes to and from each other, and a rail or projection on the log-carriage adapted to slide between the pad-boxes, as and for the purpose specified.

3. A clamp-brake for saw-mill log-carriages, having pad-boxes B B and brake-pads C C, consisting of pressed paper exposed edgewise, substantially as shown and described, and for 95 the purpose set forth.

4. A clamp-brake for saw-mill log-carriages having pad-boxes B B, brake-pads C C, and suitable operating-levers, F F, combined with rail or projection M on saw-mill carriages, as 100 and for the purpose set forth.

5. The brake mechanism for saw-mill log-

carriages, consisting, essentially, of the jaws of the clamp-brake operated by suitable levers, as described, and located between the abutments D D, as shown, combined with the rail or projection on the carriage, substantially as shown and described, and for the purpose set forth.

6. The combination of the jaws of the clamp-brake, working between abutments D D, and 10 the levers F H, fulcrumed as described, with the saw-mill carriage having a projection, as M, substantially as shown and described, and for the purpose set forth.

7. The clamping-jaws pivoted on levers F, the levers F F, pivoted on sliding blocks or fulcrums G G, which are adjustable by set-screws, as shown, and the lever H and its connections, all operating in combination, substantially as shown and described, and for the purpose set forth. 15

FRANK TUXWORTH.
